(57) **CLAIM**

The ornamental design for a cellular fire suppressant case, as shown and described.

DESCRIPTION

FIG. 1 is a perspective view of the cellular phone fire suppressant case of the instant invention in a closed position; FIG. 2 is a front view thereof;

FIG. 3 is a rear view thereof depicting two exhaust apertures;

FIG. 4 is a right side view thereof;

FIG. 5 is a left side view thereof;

FIG. 6 is a top view thereof;

FIG. 7 is a bottom view thereof

FIG. 8 is a perspective view of said cellular phone fire suppressant case in an open position depicting an fire suppressant packets placed beneath ventilated shields on the left side and on the right side;

FIG. 9 is a right side of FIG. 8;

FIG. 10 is a left side of FIG. 8;

FIG. 11 is a front of FIG. 8;

FIG. 12 is a rear view of FIG. 8;

FIG. 13 is a top plan view of FIG. 8 depicting said exhaust apertures; and,

FIG. 14 is a bottom plan view of FIG. 8.

The portions of the cellular phone fire suppressant case illustrated in broken lines form no part of the claim for the cellular phone fire suppressant case.
